UNITED STATES PATENT OFFICE.

ERNEST H. SCHMIDT, OF CLEVELAND, OHIO, ASSIGNOR TO THE NATIONAL MALLEABLE CASTINGS COMPANY, OF CLEVELAND, OHIO.

COUPLING-SHANK AND YOKE CONNECTION.

1,144,384.

Specification of Letters Patent. Patented June 29, 1915.

Application filed October 1, 1913. Serial No. 792,770.

To all whom it may concern:

- Be it known that I, ERNEST H. SCHMIDT, a citizen of the United States, residing at Cleveland, Cuyahoga county, Ohio, have invented new and useful Improvements in Coupler-Shank and Yoke Connections, of which the following is a specification, reference being had to the accompanying drawings, in which—
- 10 Figure 1 is a plan of my improved connection; Fig. 2 is an elevation thereof; Fig. 3 is a section on lines III—III of Fig. 1, and Figs. 4 and 5 are respectively side and plan views showing a modification.
- 15 My invention relates to connections between draft rigging yokes and the shanks of car couplers, and provides a simple and convenient form of connection by which the parts can be readily disconnected.
- 20 My invention also provides a yoke which has been reinforced to prevent spreading under the heavy stresses of buffing and draft.
- Referring to the drawings the numeral 2 represents the shank of an automatic coupler of any approved type. The shank 2 terminates in the butt 3 which has apertures 4 for reception of the usual rivets 5. The yoke 6, which is preferably an integral steel casting, consists of the usual 25 upper and lower arms 7 and 8 connected at their rear ends by the vertical portion 9. Upon the exterior faces of the yoke 6 is a reinforcing rib 10 which at its forward ends 11 is bifurcated to form a space within which the heads of the rivets 5 are seated. The bifurcated portions 11 serve to strengthen the forward ends of the yoke 6 at the points at which they are connected to the coupler 2.
- 30 Upon the forward inner ends of the yoke arms 7 and 8 are stops or shoulders 12, against which the forward faces 13 of the coupler butt 3 are designed to bear and which will take up the strains of draft 35 even when the rivets 5 have become broken or dislodged. The shoulders 12 are strengthened by the inwardly extending side plates 14 which are integral with the shoulders and the forward ends of the yoke arms.
- 40 The side plates 14 are adapted to bear against the sides of the coupler butt and to relieve the rivets 5 of a large proportion of the shearing stress due to side strains between the yoke and coupler when the coupler is forced to move laterally by the oper-

ation of the car. Inasmuch as the vertical distance between the side plates 14 is somewhat greater than the depth of the coupler shank, the coupler can be easily connected to the yoke by inserting the coupler laterally into the yoke with the butt to the rear of the plates 14. The coupler is then drawn forwardly until the front faces 13 of the butt 3 bear against the shoulders 12 and the side plates 14 inclose its sides. The rivets 5 may then be applied and the attachment is complete.

In the modification shown in Figs. 4 and 5 the side plates 14' are somewhat shortened and do not extend rearwardly the full length of the coupler butt, and their outside vertical faces are convergent rearwardly as shown in Fig. 5. The purpose of this modification is to decrease the overall width of the yoke at the point where it would be liable to interfere with the forward draft sill stops when the coupler moves rearwardly in buffing. Therefore with this form of my invention the forward draft sill stops need not be spaced apart laterally any extra distance on account of the lateral projection of the side plates 14'.

It is obvious that various modifications may be made in the construction which I have described and shown herein without departing from my invention.

What I claim is:

1. A draft rigging yoke having two forwardly extending arms, integral side plates at the forward end of each arm extending inwardly toward the opposite yoke arm, a coupler butt adapted to be inserted from the rear and to be drawn forwardly between said side plates and to be partially inclosed thereby, and rivets for securing the coupler to the yoke, the said plates being adapted to bear against the sides of the coupler butt and to relieve the rivets from shearing stress.
2. A draft rigging yoke having two forwardly extending arms, an external reinforcing flange about the said yoke terminating at the forward portion of each of said arms in a bifurcated reinforcement, seats for a coupler butt on the inner face of each of said arms, stop shoulders and bearing plates extending about the front and sides of said seats, and means for securing the arms and the coupler butt together.
3. A draft rigging yoke having at its for-

ward ends integral inwardly extending side plates, a coupler butt seated between and partially inclosed by said side plates and secured to said yoke, the said side plates having vertical outer faces which converge toward the rear of the coupler butt.

4. A draft rigging yoke consisting of a single-piece casting having two forwardly-extending arms, a seat for a coupler butt upon the inner horizontal face of each arm, and vertically-projecting flanges integral

with each arm extending about the front and sides respectively of each seat, the front flanges being adapted to hold the coupler against forward motion with respect to the yoke, and the side flanges being adapted to take up side strains between the yoke and the coupler.

ERNEST H. SCHMIDT.
